UNITED STATES PATENT OFFICE.

GARRY J. DORMANDY, OF LANSINGBURG, NEW YORK, ASSIGNOR TO THE UNITED SHIRT AND COLLAR COMPANY, OF TROY, NEW YORK.

MACHINE FOR FOLDING COLLAR-BLANKS, &c.

SPECIFICATION forming part of Letters Patent No. 708,030, dated September 2, 1902.

Application filed July 10, 1895. Serial No. 555,471. (No model.)

To all whom it may concern:

Be it known that I, GARRY J. DORMANDY, of the village of Lansingburg, county of Rensselaer, and State of New York, have invented 5 new and useful Improvements in Machines for Inturning the Edges of Blanks for Cuffs or Like Articles, of which the following is a specification.

My invention relates to machines for in- 10 turning or infolding the edges of blanks for cuffs or like articles; and my object is to provide an improved mechanism for operating the folders or infolders which turn in the edges of the blanks to form the folds.

15 Another object is to provide a mechanism for pressing the folds before the folded blanks are taken from the bed.

I will first describe a machine embodying my invention, and then point out the novel 20 features thereof in the claims.

Accompanying this specification, to form a part of it, there are six plates of drawings containing thirteen figures illustrating my invention, with the same designation of parts 25 by letter reference used in all of them.

Of the illustrations, Figure 1 is a top view 30 of a mechanism containing my invention, with the folders shown as moved inwardly over the edges of the blank-holder. Fig. 2 is an other top view of the same parts that are shown in Fig. 1, but with the folders moved outwardly from off the blank and the blank-holder edges. Fig. 3 is a cross-section taken 35 from front to rear on a line X' X' of Fig. 2, with the arm to which the blank-holder attaches together with the counterpoise of the arm, as well as the lever and its connection by which pressure is applied to the folders, shown in side elevation. Fig. 4 is a perspective 40 of one of the cam-pin or slide-pin plates constructed to attach adjustably to one of the slide-bars and shown as detached. Fig. 5 is a perspective of one of the slide-bars which operates the folders, shown as detached.

45 Fig. 6 is a section taken on the line X² X² of Fig. 5. Fig. 7 is a perspective of one of the folders or infolders, shown as detached. Fig. 8 is a section taken on the line X³ X³ of Fig. 7. Fig. 9 is a perspective of one of the segments, 50 showing the cam-groove or slot. Fig. 10 is a perspective of one of the presser-bars by

which pressure is applied to the top of the folders. Fig. 11 is a top view of a modification. Fig. 12 is a view of the under side of the apparatus shown at Fig. 11, and Fig. 13 55 is a section taken on the line X⁴ X⁴ of Fig. 11.

The several parts of the apparatus thus illustrated are designated by letter reference, and the function of the parts is described as follows:

60 The letters F designate the frame which supports the bed B, and the letter T designates the table on which the frame rests. This bed B is constructed with a chamber C on its under side in which steam is used or 65 gas is burned and supplied to said chamber by pipes. (Not shown.)

The letter G designates an annular slide-way or bearing which is formed in the bed B.

The letter R designates a ring arranged in 70 the slideway G, and this ring is made with a recess r², formed in its upper surface throughout its circumference, and the letter H designates a handle which is attached to the under side of the ring R, by which handle the 75 latter can be reciprocatingly rotated in the annular slideway G. While the ring R has in the drawings been shown as a complete ring this is not necessary, and I do not wish to confine myself to this form. The ring may, 80 for example, be formed in segments, so connected as to move about a common center or may be otherwise incomplete. The purpose of the ring is to constitute a slide, and while a circular form of slide has been selected as 85 the most suitable it is not essential for the reason mentioned.

The letters I designate segments, each of 90 which is provided with a slot g², vertically formed therein, preferably in a reverse curve, and each of these slots is adapted to receive a vertically-arranged slide-pin p², which is projected downwardly from the top of one of the folder-slides, and by which connection as 95 these segments are moved back and forth in reciprocation about a common center the infolders are together moved outwardly and inwardly over the bed. Each of these segments is arranged within the annular recess r² of the ring R, to thereat connect with the ring to 100 move with the latter, the connection between the ring and the segments being made by bolts

p^8 , by which one set of segments may be removed and another applied to the same machine to adapt the segments to coöperate with infolders doing different kinds of work. In 5 the modification shown at Figs. 11, 12, and 13 a series of arc-form slideways F^4 are formed around a common center in the bed B, with a ring R^2 arranged beneath the bed and with pins p^8 passing upwardly through the arc-form slots to connect the segments with the ring R^2 to move with the latter when reciprocated, and in the modification the segments are adapted to be attached and detached from the reciprocating mechanism as well as in the 10 machine first described, so that segments having different forms of slots may be used in either instance. It will be seen from this description that the slot g^2 and the pin in engagement therewith form a cam intermediate 15 of the ring and infolder, the cam being operated by the ring to effect the inward and outward movements of the infolders. While the pin is shown connected with the infolders and the cam-slot with the ring, it is evident that 20 the positions of these two parts may be reversed and the same result effected through the cam action.

The letters F^2 designate folders, of which 30 there are four shown as applied to the machine illustrated. Each of these folders has an L form, and they are arranged so that the surface of the folders at their inner edges will inclose an oblong square, with the inner side edges f^2 in alinement and also the end edges f^3 in alinement with each other. One 35 of these folders or infolders is shown as detached at Figs. 7 and 8, and the one shown there is in form and construction a counterpart of the others. Each of these folders is 40 provided with inwardly-projecting side edges e^2 and inwardly-projected end edges e' . Each of these folders F^2 is provided with an overhanging side a^2 , having thereon a downwardly-projecting rib a' , and they are each 45 cut away at a^4 for the passage of the presser-shanks, and they are each made with a slot a^3 , by which they are adapted to adjustably connect with that one of the slide-bars which operates them.

50 The letter S designates slideways formed on the top of the bed B for the movement therein of the slide-bars which operate the infolders, and these slideways S are produced between the bars $b^2 b^2$, which are attached to 55 the top of the bed B in each instance of their use, there being four of them, one for the slide-bar of each of the infolders. All of these infolders have a small measure of vertical movement as mounted in their slideways 60 to permit their operating to press down the infolds when moved downwardly by the action of the pressers, as will be more fully detailed hereinafter.

The letters N designate slide-bars, of which 65 there is one arranged in each of the slideways S. Each of these slide-bars is for adjustment, attachment, and detachment connect-

ed at its inner end with a bar n^2 at an angle, and each of these bars n^2 has a ledge g^5 , provided with a groove g^4 , formed in its upper 70 surface, by which it is adapted to tongue into so as to enter by underrunning the ribbed surface formed in the overhang a^2 of the folder F^2 , with which the slide-bar connects at n^4 by means of a slot a^3 in the infolder and 75 the bolt b^4 , having a head-nut h^2 straddling said slot and passing through the bar n^2 at n^4 .

The letters O designate recesses formed longitudinally in each of the slide-bars N, said recesses each having a bottom opening 80 or slot o^2 , as shown at Fig. 5.

The letter M designates a cam-pin plate, of which there is one for each of the slide-bars N. Each of these cam-pin plates M is provided with a cam-pin p^2 , which at its lower 85 end is constructed with a cam-roller p^3 , each of which latter when in position in the machine will be entered in one of the cam-slots g^2 , formed in each of the segments I, it passing down through the opening o^2 to make such 90 connection. As thus constructed and arranged when the ring R is reciprocated within the annular slideway G of the bed by means of the handle H the segments I, by 95 means of the connections which the cam-rollers on the pins p^2 make in sliding engagement with the sides of the segment-slot, the connected slide-bars, and infolders, will be moved outwardly and inwardly, and when the modifications shown at Figs. 11, 12, and 13 are used and 100 when the ring R^2 is reciprocatingly rotated the connection made with the infolders by means of the slide-bars and the connection the latter each make with one of the segment cam-slots the infolders are moved outwardly 105 and inwardly in the same manner as when actuated by the ring R. Each of the cam-pin plates M adjustably connects with one of the slide-bars N, by means of a slot m^3 , made in said plates, and a heavy bolt b^5 , passing 110 through said slot and the opening o^2 in the bottom of the bar N, with a nut on the lower end of the bolt straddling the under side edges of the opening o^2 .

The letters P designate the folder-pressers, 115 of which there are two for each folder. Each of these pressers P has a laterally-extended head p^5 arranged thereon at right angles to its shank s^2 , with the inner end of each of the presser-heads arranged to project inwardly over the folders, there being one of these pressers arranged to overhang the end and another the side of each of the folders F^2 , one of these pressers being shown at Fig. 10 illustrated as detached from the machine, 120 the function of the pressers being as operated to bear down upon the folders and to press into the blanks the infolds formed on their outer edges when located between the 125 folders and the bed and before the folders have been moved outwardly. The shanks s^2 of these pressers pass downwardly loosely through the bed B at o^3 , and thereat they are each threaded at t' , and by means of nuts $t^2 t^2$ 130

they are adjustably connected to the top plate of the presser-frame T³. This frame consists of a top plate A, having downwardly and inwardly tapering end plates E E, with the top plate A cut away at ⁵ t⁵.

The letter B⁴ designates a bottom bar, which at its ends connects with the frame ends E, and the letters S⁴ designate springs, of which there is one arranged between said bottom bar ¹⁰ B⁴ and the table T at each end of said bar. The office of these springs is to lift the bar B⁴ and its attached mechanism, so that the folder-pressers F will be elevated and raised from off the folders after the latter have been actuated to press in the infolds, as will be detailed hereinafter.

The letter J designates a bar, which at its upper ends connects with the under side of the bed B to depend therefrom and below, ²⁰ where passing through the cut-away part of the top plate A, it pivotally connects with a lever L, resting upon the top of the horizontal bar B⁴, with the outer end of the lever L connecting pivotally with a foot-treadle V by ²⁵ means of a rod U, and by which construction and connection when the foot-treadle is depressed the lever L will bear downwardly upon the horizontal bar B⁴ to pull downwardly the presser-frame and pressers, with the latter bearing downwardly upon the folders F² to press the infolds between the infolders and the bed against the recoil force of the springs S⁴, which latter when the pressure upon the foot-treadle is released become active to raise ³⁰ the pressers from off the infolders.

The blank-holder H² is provided with two plates k' k' on one of the sides of the holder and the plates k² k² on its other side. Each of these plates k' k' connects with a slide-bar ⁴⁰ u², of which there is one for each of the plates k', arranged in a slideway u⁴ on one side of the stock h², and the plates k² k² each connect with a slide-bar u³, arranged in a slideway u⁵ upon that side of the holder-stock ⁴⁵ k', which is opposite to that in which the plates k', their slide-bar, and slideways are located.

The letters C C designate cam-plates, of which there is one at each end of the holder-stock and each of which cam-plates is adapted ⁵⁰ to move outwardly and inwardly in a slideway located centrally between and parallel to the stock sides at each end of the holder and which slideway is not shown. Each of these cam-plates is constructed with oppositely-placed cam-slots c³ and c⁴, there being one of the latter upon each side of each of the cam-plates C and with the cam-slots c³ of each of the cam-plates upon one side of the slot and the cam-slots c⁴ upon the other side ⁵⁵ of the slot. Each of the slots c³ of each of the plates C opens out from the side of the latter at an angle, which will give to the slide-pins p⁷, moving therein, more sidewise movement of outthrow than is given to the pin ⁶⁰ moving in the slots c⁴ upon the other side of the plates C, and the slideways u⁴, formed in the stock for the slide-bars u², open out from

the slot sides at such an angle as will give to said slide-bars u² more outthrow lengthwise of the stock than the sideways u⁵ in which ⁷⁰ the slide-bars u³ move. The slots c⁴ of each of the cam-plates C receives one of the cam-pins p⁷, connected to one of the slide-bars u³, and each of the cam-slots c³ of each of the cam-plates C receives one of the cam-pins p⁷, ⁷⁵ connected to one of the slide-bars u².

The letter D designates a wheel which is journaled at d⁴ to the top of the holder-stock, and this wheel is provided with an operating-handle h⁶. This wheel has formed in it the ⁸⁰ slots d⁷ and d⁸, and they are arranged to be formed therein at each side of the pivotal connection b⁴.

The letter L⁴ designates a link which at its inner end connects with a slide-pin p⁹, arranged to move in sliding engagement with the slot d⁷, and at its outer end this link L⁴ pivotally connects with one of the cam-plates C at m⁶. The letter L⁵ designates another link, the outer end of which pivotally connects with the other cam-plate C at m⁷, and at its inner end this link L⁵ connects with the slide-pin p⁹, arranged to move within and make a cam or sliding engagement with the slot d⁸ of the wheel D. As thus made and ⁹⁰ connected, as the handle h⁶ of the wheel D is reciprocated horizontally the cam-plates C are moved outwardly and inwardly, and the cam-plates operate the holder-plates k' upon one side of the slot and the plate k² upon the ⁹⁵ other side of the slot to move outwardly and inwardly. Each of the holder-plates k' is cut away on an angle at its inner edge near its outer end, as shown at a⁷, and each of the plates k² on its inner edge near its outer end ¹⁰⁰ is cut away on an angle a⁸, and by which construction when the plates are moved outwardly by the wheel and link connections the outer edge of the holder-plates k' and k² will at each end of the holder be in alinement ¹⁰⁵ and form a continuous infolding edge thereat, and when the plates are drawn inwardly (in consequence of one of them having more outthrow than the other) one of them will slide ¹¹⁰ within the other.

The letters A⁴ designate an arm which is hinged at its rear end to the rear of the machine-table at m⁹, and where extending beyond its hinged connection this arm is connected with a counterpoise W⁴, by which latter the arm is held raised from off the bed when the blank-holder H² is not in use.

The letter h⁶ designates a handle by which the arm A⁴ may be pulled downwardly on its hinged connection, so that the blank-holder ¹²⁰ H² will rest on the machine-bed or on a blank placed thereon, this handle h⁶ being the same handle that is used to operate the wheel D and its connections to move outwardly and inwardly the holder-plate.

As thus constructed and arranged to operate, with the blank-holder raised from off the bed and a blank having been placed on the bed the holder is actuated to descend upon ¹³⁰

the blank with its plates expanded and resting upon the blank, when the segment-ring is moved in rotation to move inwardly the holders, so as to carry the subtending edges 5 of the blank over the edges of the expanded holder-plates, when all the latter are drawn inwardly from out the infolds by the operation of the handle h^6 and the wheel D, when the foot-treadle is operated to force the 10 pressers P to contact with the tops of the folders F² to press downwardly the latter, and thus press the infolds made between the folders and the bed, when the holder is raised and the segment-ring is operated to draw outwardly 15 the folders, when the infolded and pressed blank is raised from the bed.

By the employment of segments having cam-slots formed therein, with said segments attachable and detachable from the ring by 20 which the segments are operated to actuate the slide-pins of the infolder slide-bars, segments having differing measures of cam-slot curve and form may be used to operate folders for infolding differing forms of work and 25 by the same machine, which could not be accomplished by a device in which the cam-slots were permanently located in an eccentrically-operated ring and arranged to actuate infolders made to tongue into each other at 30 their side edges and provided with cam-pins on their outer ends, making a sliding engagement with one of the permanently-located slots in the eccentrically-operated ring, such as has been patented for bookbinder uses.

35 By the connection made between the cam-pin plates M and the slide-bars N, as hereinbefore described, the slide-bars are made adjustable to the cam-pin plates and by means of the latter to the segment-slots of differing 40 segments, while the slide-bars N are made adjustable to and detachable from the infolders F, as hereinbefore described, whereby one machine is adapted for infolding blanks of differing forms.

45 Where in the claims and elsewhere herein it is set forth that one part effects the actuation of another, as that the cam-ring or cam effects inward and outward movements of infolders, I of course intend the broader meaning of the word "effect"—i. e., to bring about or cause.

To the templet or blank-holder herein shown and described no claim is made herein apart from its combination with the mechanisms 55 for operating the infolders of cuff and collar infolding machines with which it is shown to coöperate, this form of templet or blank-holder being made the subject of another application for Letters Patent filed by me and 60 known as Serial No. 554,586, and which is now pending.

As the pressers P herein shown and described would perform the same function in the same manner whether applied to the 65 folders which I illustrate and describe or to other forms of infolders actuated in like manner, I do not limit my invention of the press-

ers to their combination with the infolders, to which I show them as applied.

While I have illustrated my invention as 70 applied to a machine for infolding the edges of cuff-blanks, it is equally applicable by slight changes to the infolding of other and analogous articles—as, for example, the blanks of collars.

Having thus described my invention, what I claim, and desire to secure by Letters Patent, is—

1. In a machine for infolding cuff-blanks or analogous articles, the combination of a 80 support for the blanks, a templet having edge portions adapted to bear directly upon the blanks upon said support and within edge portions of the blanks, infolders constructed and fitted to move inwardly and outwardly 85 whereby edge portions of the blanks may be folded over edge portions of the templet, a slide constructed and fitted to move to and fro, and a plurality of devices, as cams, actuated by the said slide, each device for effecting 90 the inward and outward movements of one or more infolders.

2. In a machine for infolding cuff-blanks or analogous articles, the combination of a support for the blanks, a templet having edge 95 portions adapted to bear directly upon the blanks upon said support, and within edge portions of the blanks, infolders constructed to move inwardly and outwardly whereby the edge portions of the blanks may be folded 100 over the edge portions of the templet, a ring constructed and fitted to slide in bearings located outward of the blanks upon said support, and means intermediate of said ring and of infolders, whereby the said ring may effect 105 the inward and outward movement of infolders.

3. In a machine for infolding cuff-blanks or analogous articles, the combination of a support for the blanks, a templet having edge 110 portions adapted to bear directly upon the blanks upon said support and within edge portions of the blanks, infolders constructed to move inwardly and outwardly whereby the edge portions of the blanks may be folded 115 over the edge portions of the templet, a ring, and a plurality of cams provided in said ring, each for effecting the inward and outward movements of one or more infolders.

4. In a machine for infolding cuff-blanks or analogous articles, the combination of a support for the blanks, a templet having edge 120 portions adapted to bear directly upon the blanks upon said support and within edge portions of the blanks, infolders constructed 125 to move inwardly and outwardly whereby edge portions of the blanks may be folded over edge portions of the templet, a ring constructed and fitted to move to and fro, the said ring located outward of the blanks upon 130 said support, and means actuated by said ring for effecting the inward and outward movements of infolders.

5. In a machine for infolding cuff-blanks

- or analogous articles, the combination of a support for the blanks, a templet having edge portions adapted to bear directly upon the blanks upon said support, and within edge portions of the blanks, a ring constructed and fitted to slide in suitable bearings provided in said support, infolder-bars constructed and fitted to move inwardly and outwardly, the said bars located above the said sliding ring, cams actuated by said ring for effecting the inward and outward movements of infolder-bars and infolders connected to the infolder-bars.
6. In a machine for infolding cuff-blanks or analogous articles, the combination of a support for the blanks, a templet having expanding and contracting plates, edge portions of which are adapted to bear directly upon the blanks upon said support and within edge portions of the blanks, a ring constructed and fitted to slide in suitable bearings in said support, slide-bars constructed to move inwardly and outwardly, slideways for said slide-bars, the said slideways being connected to the said support above the said sliding ring, cam-surfaces provided upon the said ring, cam-pins downwardly projecting from said slide-bars for engaging with said cam-surfaces, whereby the said ring may effect the inward and outward movements of slide-bars, infolders connected to slide-bars, means for sliding said ring to and fro whereby infolders may be moved inwardly and outwardly to fold edge portions of the blanks over edge portions of said templet, and means whereby the folds of the blanks may be pressed between the support and infolders after withdrawal of the plates of the templet from the folds, and thereby fixed with a sharp fold.
7. In a machine for infolding cuff-blanks or analogous articles, the combination of a support for the blanks, the support provided with an annular bearing, infolders constructed to move inwardly and outwardly whereby edge portions of the blanks may be infolded, a ring constructed and fitted to slide in the bearing in said support, means for oscillating said ring, means intermediate of said ring and of infolders whereby the oscillation of said ring may effect the inward and outward movements of infolders, and means whereby the folds of the blank may be pressed between the support and infolders and before the blanks are taken from the said support, and thereby fixed with a sharp fold.
8. In a machine for infolding cuff-blanks or analogous articles, the combination of a support for the blanks to be infolded, a templet for defining the blanks upon said support, infolders for infolding edge portions of the blanks over edge portions of the templet, bars connected to said infolders constructed and fitted to move inwardly and outwardly, guides for said bars, the said guides being separate from said support and attachable to and detachable from the support, a ring fitted to move to and fro and cams actuated by the ring for effecting the inward and outward movements of the said bars and the infolders connected thereto, the said cams being separate from the ring and attachable to and detachable from the ring.
9. In a machine for infolding cuff-blanks or analogous articles, the combination of a support for the blanks to be infolded, a templet for defining the blanks upon said support, infolders for infolding edge portions of the blanks over edge portions of the templet, bars connected to said infolders constructed and fitted to move inwardly and outwardly, a part fitted to move to and fro, cams actuated by said part for effecting the inward and outward movements of the bars, and means adjustably connecting the cams and bars, whereby the cams may be longitudinally adjustable upon the bars, so that the infolders may be adapted to the infolding of blanks of varying dimensions.
10. In a machine for infolding cuff-blanks or analogous articles, the combination of a support for the blanks to be infolded, a templet for defining the blanks upon said support, infolders for infolding edge portions of the blanks over edge portions of the templet, bars constructed and fitted to move inwardly and outwardly, means connecting infolders and bars whereby the infolders may be laterally adjustable at the inner ends of the bars, a part fitted to move to and fro, cams actuated by said part for effecting the inward and outward movements of the bars, and means adjustably connecting the cams and bars, whereby the cams may be longitudinally adjustable upon the bars, so that the infolders may be adapted to the infolding of blanks of varying lengths and widths.
11. In a machine for infolding cuff-blanks or analogous articles, the combination of a support for the blanks, a templet having edge portions adapted to bear directly upon the blanks upon said support and within edge portions of the blanks, infolders constructed to move inwardly and outwardly, whereby edge portions of the blanks may be folded over edge portions of the templet, means for effecting the inward and outward movements of said infolders, a part fitted to said machine having upwardly-projecting members, with heads adapted to extend over said infolders when the latter are moved inwardly, and means for depressing said part whereby it may cause the infolders which are moved inwardly to descend toward said support to press and thereby to fix with a sharp fold the infolds of the blanks beneath said infolders.
12. In a machine for infolding cuff-blanks or analogous articles, the combination of a support for the blanks to be infolded, infolders fitted to said support to move inwardly and outwardly whereby the blanks upon said support may be infolded, said infolders be-

- ing adapted to receive a slight vertical movement sufficient to press with a sharp fold the infolds of the blanks between the said infolders and said support, a treadle, and means 5 intermediate of said treadle and said infolders, whereby the said treadle may effect the vertical movements of the said infolders to press the blanks.
13. In a machine for infolding cuff-blanks or analogous articles, the combination of a bed for supporting the blanks, a ring fitted to the bed to oscillate, means for oscillating said ring, slides fitted to move inwardly and outwardly on said bed, infolders connected 10 to slides, and cams intermediate of said slides and said ring, whereby when the ring is oscillated infolders may be moved inwardly and outwardly.
14. In a machine for infolding cuff-blanks or analogous articles, the combination of a bed, a ring fitted to the bed to oscillate, segments detachably connected to said ring to oscillate therewith and provided with cam-surfaces, inwardly and outwardly moving 15 slides provided with cam parts for coacting with the cam-surfaces of said segments, infolders connected to said slides and means for oscillating said ring to effect inward and outward movements of infolders.
15. In a machine for infolding cuff-blanks or analogous articles, the combination of a bed, infolders, the bed provided with a circular slideway, a ring capable of sliding in said slideway, the ring provided with a concentric groove, a cam for operating an infolder connected to said ring through the groove therein, and means for moving said ring whereby the infolder may be operated to infold an edge portion of a blank upon said bed.
16. In a machine for inturning the edges of blanks for cuffs or like articles, the combination with a bed having a circular slideway, and also radially-arranged slideways of infolders each provided with a slide-bar arranged in one of said radial slideways, a ring arranged in said circular slideway and provided with a handle by which to be reciprocatingly rotated therein; segments each having a cam-slot and connected to said ring; a 40 slide-pin arranged to make a sliding engagement with the sides of each of the segment-slots, and mounted upon a plate adjustably connected to one of said slide-bars, whereby as said ring is reciprocated in said circular slideway the infolders will be moved inwardly and outwardly substantially as and for the purposes set forth.
17. In a machine for infolding the edges of blanks for cuffs or like articles, the combination with a bed provided with an annular slideway; of a ring having an annular groove, and arranged in said slideway and provided with an operating-handle; radially-arranged slideways formed in said bed; segments each 45 provided with a cam-slot and interchangeably connected to said ring within said annular groove; infolders each having a slide-bar arranged in one of said radial slideways; a slide-pin mounted upon a plate adjustably connected to the outer end of each of said slide-bars, and arranged to make a sliding engagement with the cam-slot of one of the segments whereby as said ring is reciprocatingly rotated the infolders will be moved inwardly and outwardly over the bed, substantially as and for the purposes set forth. 70
18. The combination with the bed B, having the annular slideway G, and radially-arranged slideways S; of the ring R, having the annular recess r^2 , in its upper surface, and provided with an operating-handle H; the segments I, detachably connected to, and arranged within said annular slideway, and each provided with the cam-slot g^2 ; the slide-bars N, each arranged in one of said radially-arranged slideways, and each provided with a slide-pin p^2 , with each of the latter arranged to engage with the slot g^2 , of one of the segments; and an infolder F², connected to the inner end of each of said slide-bars, 80 constructed and arranged to operate substantially as and for the purposes set forth. 85
19. In a mechanism for infolding the edges of blanks for cuffs or like articles, the combination with a bed provided with an annular slideway; of a ring constructed with an annular recess and provided with an operating-handle by which to be reciprocatingly rotated in said annular slideway; segments each provided with a cam-slot, and each detachably connected to said ring; slideways radially arranged on said bed; a slide-bar arranged in each of said radial slideways; and each provided with a slide-pin, making a cam or sliding engagement with the cam-slot 90 of one of the segments; an infolder for each of said slide-bars; and means substantially as described for adjustably connecting each of said infolders to one of said slide-bars, constructed and arranged to be operated substantially in the manner as and for the purposes set forth. 95
20. The combination with the folders F², each provided with the slot a^3 , and ribbed overhanging side a^2 , of the slide-bars N, each 100 provided with a slide-pin p^2 , and having a grooved ledge g^5 and each attached to one of said folders by means of the slot a^3 , and bolt b^4 , and segments each provided with a curved slot adapted to receive the slide-pin of each 105 of said slide-bars, with said segments operated to be reciprocatingly rotated on the machine-bed, substantially as and for the purposes set forth. 110
21. The combination with the folders F², the slide-bars N, each having the recess O, provided with the bottom opening O², of the cam-pin plates M, each made with the slot d^3 , and having the downwardly-projected cam-pin p^2 , the ring R, arranged in the annular recess G, 115 the segmental plates I, each having a cam-pin slot g^2 , constructed to connect and be operated. 120

ted substantially in the manner as and for the purposes set forth.

22. The combination with a series of folders arranged upon a bed, each provided with a slide-bar whereby they may be moved inwardly toward or outwardly from each other substantially as described; of pressers each having a vertical shank passing down through the bed, and each having a laterally-extended head that will overhang the folders when the latter are moved inwardly; a frame to which the shanks of the pressers attach, and a lever operated by a treadle whereby said frame may be drawn downwardly and cause the presser-heads to bear on the folders against the force of a spring, substantially in the manner as and for the purposes set forth.

23. The combination with the bed B, of the frame T³, the pressers P, attached to the latter and upwardly projected therefrom and each provided with an overhanging head p⁵, the lever L, provided with a foot-treadle, and connecting-rod; and the folders F², arranged on said bed beneath the overhanging heads of the pressers, constructed and arranged to be operated substantially in the manner as and for the purposes set forth.

24. The combination with the frame T³, of the pressers P, each made with a laterally-extended head p⁵, and having a downwardly-projected shank connected to said frame; the folders F²; the spring S⁴, arranged between said frame and the machine-table, and the lever L, provided with a foot-treadle, and connecting-rod constructed and arranged to operate substantially as and for the purposes set forth.

25. The combination with the bed B, provided with slideways S, of the slide-bars N, each connected to a bar n², and arranged in one of the slideways; the folders F², each connected to one of said bars n²; the frame T³; the pressers P, each having the laterally-extended head p⁵, and provided with a shank projected downwardly to connect with a frame beneath the bed, and the lever L, constructed and arranged to be operated substantially in the manner as and for the purposes set forth.

26. The combination with a bed having an annular slideway formed therein; of a ring constructed to be reciprocatingly rotated in said annular slideway; segments each provided with a cam-slot, and attached to said ring; slide-bars each provided with slideways and having a cam-pin plate provided with a cam-pin entered in one of the segment-slots; a folder attached to each of slide-bars; a blank-holder having a hinged connection with the bed, at one side thereof; pressers each provided with an overhanging head, and connected to a frame beneath the bed; and a lever having a treadle whereby said frame may be moved downwardly with the heads of the pressers bearing upon said folders, substan-

tially in the manner as and for the purposes set forth.

27. In a machine for inturning the edges of blanks for cuffs or like articles, the combination with a bed of a ring provided with a circular slideway formed in said bed, and provided with means to be reciprocatingly rotated therein substantially as described; segments each provided with a cam-slot and constructed to be detachably connected to said ring; infolders each provided with a slide-bar, and a slideway on the bed; a slide-pin mounted on a plate adjustably connected to each of said slide-bars at its outer end and thereat arranged to engage with the sides of one of said cam-slots; and a templet having expanding and indrawing plates upon its under surface, and provided with means whereby it may be operated to descend onto and rise from off said bed, substantially as and for the purposes set forth.

28. In an infolding-machine, the combination with a bed having an annular slideway and radially-arranged slideways; of a ring provided with an annular recess, and a handle by which to be reciprocatingly rotated in said annular slideway; infolders each having a slide-bar arranged in one of said radial slideways, each of said slide-bars having mounted thereon adjustably a plate having at its outer end a slide-pin; segments each provided with a cam-slot adapted to receive one of said slide-pins, said segments being connected in a detachable manner to said ring substantially as and for the purposes set forth.

29. In an infolding-machine, the combination with a bed provided with a circular slideway, and radially-arranged slideways, of a ring provided with a handle by which to be reciprocatingly rotated in said circular slideway; segments each provided with a cam-slot; means substantially as described whereby said segments are detachably connected to said ring; a slide-bar in each of said radial slideways provided with a cam-pin plate having on its outer end a cam-pin arranged to run in one of the said cam-slots; and an infolder mounted on the inner end of each of said slide-bars constructed and arranged to be operated substantially in the manner as and for the purposes set forth.

30. In a machine for infolding blanks for cuffs or like articles, the combination with a bed having an annular slideway and radially-arranged slideways; of a ring provided with a handle by which to be reciprocated in said annular slideway; segments each provided with a cam-slot and connected to said ring; infolders each provided with a slide-bar arranged in one of said radial slideways; a slide-pin mounted upon the outer end of a plate connected to each of said slide-bars, said slide-pins each making a sliding engagement with the slot of one of the segments; and a blank-holder having expanding and

indrawing plates on its under surface, and means substantially as described whereby said blank-holder may be operated to descend onto and rise from off said bed, substantially in the manner as, and for the purposes set forth.

Signed at Lansingburg, New York, this

6th day of June, 1895, and in the presence of the two witnesses whose names are hereto written.

GARRY J. DORMANDY.
